US00D793444S

(12) **United States Design Patent** (10) **Patent No.:** **US D793,444 S**
(45) **Date of Patent:** **** Aug. 1, 2017**

(54) **DISPLAY SCREEN OR PORTION THEREOF WITH ICON**

(71) Applicant: **Samsung Electronics Co., Ltd.**, Suwon-si (KR)

(72) Inventors: **Jihoon Kim**, Seoul (KR); **Junghoon Kim**, Seoul (KR); **Jin-Gyu Seo**, Namyangju-si (KR); **Jiyoon Lee**, Seoul (KR)

(73) Assignee: **Samsung Electronics Co., Ltd.**, Suwon-si (KR)

(**) Term: **15 Years**

(21) Appl. No.: **29/559,076**

(22) Filed: **Mar. 24, 2016**

(30) **Foreign Application Priority Data**

Nov. 11, 2015 (KR) 30-2015-0056847
(51) **LOC (10) Cl.** **14-04**

(52) **U.S. Cl.**
USPC **D14/492**

(57) **CLAIM**

We claim the ornamental design for a display screen or portion thereof with icon, as shown and described.

DESCRIPTION

The sole FIGURE is a front view of a display screen or portion thereof with icon showing our new design.

The dot-dash broken lines in the FIGURE illustrate the display screen or portion thereof and form no part of the claimed design.

1 Claim, 1 Drawing Sheet
